UNITED STATES PATENT OFFICE.

ANTHONY L. WORACEK, OF NEW YORK, N. Y.

DESIGN FOR A FIXED DIAL FOR A UNIVERSAL STANDARD-TIME CLOCK FACE.

Application filed November 14, 1927. Serial No. 24,124. Term of patent 14 years.

To all whom it may concern:

Be it known that I, ANTHONY L. WORACEK, a citizen of the United States, residing at New York, in the county of New York and State of New York, have invented a new, original, and ornamental Design for Fixed Dials for Universal Standard-Time Clock Faces, of which the following is a specification, reference being had to the accompanying drawing, forming part thereof.

The figure is a face view of the fixed dial with the co-operative manually turned dial in dotted lines.

I claim:

The ornamental design for a fixed dial for a universal standard-time clock face, as shown and described.

ANTHONY L. WORACEK.
